UNITED STATES PATENT OFFICE.

ARCHABALD T. BOYKIN, OF CARBON, TEXAS.

AIR MOTOR.

Application filed March 24, 1923, Serial No. 627,478. Renewed July 27, 1925.

To all whom it may concern:

Be it known that ARCHABALD T. BOYKIN, a citizen of the United States of America, residing at Carbon, in the county of Eastland 5 and State of Texas, has invented certain new and useful Improvements in Air Motors, of which the following is a specification.

This invention relates to improvements in air motors, and is an improvement on the apparatus covered in my copending application, Serial Number 504,961.

In general, the present arrangement is similar to that set forth in my copending application, and the objects thereof in general 15 may be attributed to the present construction.

Among the objects of the present invention, in addition to improving upon my former apparatus, is to provide a novel construction and arrangement of the bearings 20 for the wind wheel and its shaft and the wind shield, further features residing in the specific arrangement of the wind-vane and governor connection with the wind 25 shield, and the means whereby the apparatus may be automatically or manually controlled.

In the accompanying drawings:

Figure 1 is a side elevation of the apparatus complete.

Figure 2 is a top plan view thereof;

Figure 3 is a top plan view showing different position;

Figure 4, a horizontal section through the 35 wind-wheel, and

Figure 5 is a transverse section through the wind-wheel, parts being broken away; and

Figures 6, 7 and 8 are detail sectional 40 views of important features.

Referring now to the accompanying drawings, by numerals of reference, 10 indicates a supporting tower upon which is mounted the wind-wheel to be later described, said 45 tower, except for details herein set forth, being substantially similar to that in my copending application, Serial Number 504,961, filed October 3, 1921.

The present structure differs from that of 50 the aforementioned application in the following:

Mounted below the apex of the tower, on cross-bars, is a metal rectangular plate 14 having upon opposite sides, flanges 15 which 55 overhang the cross-bars, and to which they are secured by bolts. The plate has a cen-

tral recess adapted to receive the lower end of the driving or power shaft 18. The plate is further provided with a pair of depending flanges 19 which provide bearing means for 60 the end of a horizontal rotary shaft 20 upon the inner end of which is fixed a gear 22 extending upwardly through a slot 24 in said plate and meshing with a gear 25 mounted adjacent the lower end of the power shaft 18. 65

Fixed upon the upper apex or end of the tower is a cap or collar 29, secured in place through rivets or bolts, and upon this cap is mounted and suitably fastened, a rectangular plate 30, having a rigid upstanding tubular bearing shaft 31, the upper end of which is threaded and provided with a wind-vane retaining nut 32. The inner upper and lower ends are also provided with bearing collars 70 to support the wind-vane shaft against lateral movements. 75

The wind-wheel comprises a cylinder 34 reinforced at each end upon the inside by bands or rings 25 riveted in position. The support for the wind-wheel comprises a 80 shaft 36, having an upper squared end which is terminally screw threaded at 33, said shaft extending axially through the cylinder 34, the squared end cooperating with a similarly shaped apertured casting or spider 38 having four radial apertured flanges 39 upon which are respectively fixed longitudinally extending arms 40. The ends of the arms are bolted or riveted respectively to the opposite ends of the cylinder, said bolts passing through the reinforcing bands 35. After the spider 38 has been seated upon the squared end of the shaft 36, a nut is applied to the threaded terminal 33, to bind the wind-wheel. The cylinder is provided with an annular series of radial blades 42 secured in position through bolted flanges, 44, maintained in proper spaced relation at their outer vertical edges through spacing and bracing rods 45, having terminal hooks 46, which cooperate with perforations 48 in the blades. The shaft 36 is of course formed with or at least connected for rotation with the power shaft 18, this detail of construction being left to the manufacturers. 95

The wind-wheel operates within a semi-circular drum-shaped shield, 50, reinforced around the margin of its opening by a reinforcing metallic strap 51 riveted in position, the lower face of the drum 51 being provided with a centrally located marginal notch for the reception of the lower end of a tube 53, 100 105 110

- having a pair of spaced collars 54. These collars respectively engage upon opposite sides of the lower face of the drum adjacent the marginal notch and are clamped by bolts 55,—a spacing sheet 56 being interposed between said collars at their outer portions.
- The shield 50 is yieldingly held in a position to expose a portion of the wind-wheel blades through the medium of a wind-vane 10 60 mounted upon the outer end of the horizontal arm 61, the inner end of said arm being rigidly connected with one side of a metallic loop 66, the latter being pivotally mounted upon a stub shaft 62 rigid with 15 and extending upwardly from the upper central portion of the reinforcing band or strap 51. The upper end of the stub shaft 62 is threaded to receive a nut for maintaining the loop 66 in operative position.
- 20 Extending horizontally from the loop 66, in a line with but diametrically opposite from the wind-vane carrying arm 61, is a weighted or counterbalancing arm 65 from the upper face of which projects a lateral 25 spring latch 68, adapted to cooperate under conditions to be later specified with a catch 69, catch 69 being arranged of course, in the path of movement of the latch 68.
- For the purpose of maintaining under 30 normal conditions, the wind-shield responsive to the control of the wind-vane, I provide a coil torsion-spring 72 which encircles the strip shaft 62 and is connected at its ends respectively to a portion of the loop 35 and to a radial pin on said stub shaft. The movement of the wind-vane arm is limited in its movement from swinging over the upper face of the shield through a fixed stop pin or lug 74.
- 40 While the wind-vane, under normal conditions, maintains the shield in a position to expose certain of the wind-wheel blades, and permits operation of the wind-wheel, it is necessary, under abnormal wind conditions, such as exists during a storm, to render the said wind-wheel inoperative and thus prevent racing thereof which is injurious to the whole mechanism for reasons unnecessary to state.
- 45 50 To overcome this latter contingency, I provide the shield with a governing mechanism which comprises an arm 78 which is secured by suitable fastening devices 79 to the upper face of the said shield and includes an extension 80 which normally lies at an angle of substantially 135 degrees with relation to the wind-vane arm 61, and carries at its terminal, a governor disk or blade 82, disposed in a vertical plane.
- 55 60 Arranged on the rear portion of the arm 78 is the catch 69 previously referred to, this catch being formed by an upturned flange on said arm and cooperating with the spring latch 68, carried by the counterbalanced portion 65 of the wind-vane,

Pivots mounted upon this flange is a release trigger 83, which is normally rigid to non-releasing position through a spring 84. Connected with the outer end of the trigger 83, is a rope or cord 86, which is convenient to the operator upon the ground, the free end being preferably, supplied with a length of iron rod to cause the cord to hang vertically.

Under normal conditions, the wind-vane 75 will yieldingly maintain the shield in a position to uncover the blades, but under stress of abnormal air currents, the pressure of the air upon the governor blade will cause it to swing in the direction of the flow of 80 the wind, overcoming the tension of the corded spring, and the wind-vane being held in a position parallel with the air currents due to its greater area exposed to air pressure will permit the shield to swing with the 85 governor to cover the wind wheel and render it non-effective. It is understood that the governor is operative only when the air pressure thereon overcomes the tension of the coil spring. If the pressure exerted 90 upon the governor blade is sufficient it will cause the shield to be swung to such an extent that the spring latch 69 will engage the catch 70 and maintain said shield in a position to fully cover the wind wheel blades. 95 Under these conditions to throw the wind wheel again into operative position, it is necessary for the operator to pull the trigger cord 86 which trips the latch and permits the tension spring to move the shield to uncovering position, to a degree dependent upon the pressure then exerted upon the governor blade.

Under certain conditions, the operator may wish to manually render the wind wheel inoperative, such for example when repair of parts is necessary. To this end, I provide upon the upper face of the shield, adjacent to the inner end of the governor arm, a swivelled pulley 90 over which passes a pull 100 cord 92, secured at one end to an eye 96 attached to the outer end of the counterbalance 65, the free end being weighted and extending toward the ground within reach 11 of the operator. By a pull on the cord 92, the shield is manually moved into the wind-vane covering position and latched in the same manner as in the case of the automatic operation by the governor.

Having thus described my invention, what I claim as new is:—

In an apparatus of the class described, a tower, a wind wheel rotatably mounted upon the upper end thereof, a semi-circular drum-shaped shield pivoted for oscillation 12 on the upper end of said tower, and partially surrounding said wind wheel, a wind-vane supported upon said shield, a yielding connection between said shield and said wind-vane, a counterbalance for said wind 13

vane having a latch, a governor arm rigidly mounted upon the top of said shield, and having a governor blade at the outer end thereof, disposed in a vertical plane, a catch 5 arranged on said shield adjacent the inner end of the governor arm and adapted to coact with the latch on the counterbalance,

when said shield is moved by the pressure of wind on said governor blade, and means for releasing said latch.

10

In testimony whereof I affix my signature.

ARCHABALD T. BOYKIN.
